US00D770952S

(12) **United States Design Patent** (10) **Patent No.:** **US D770,952 S**
Heilaneh et al. (45) **Date of Patent:** **** Nov. 8, 2016**

(54) **SIDE PANEL ROOF FAIRING**

(71) Applicants: **Louis D. Heilaneh**, Lewisville, TX (US); **Hanson Morris**, Fort Worth, TX (US); **Bradley D. Powell**, Corinth, TX (US)

(72) Inventors: **Louis D. Heilaneh**, Lewisville, TX (US); **Hanson Morris**, Fort Worth, TX (US); **Bradley D. Powell**, Corinth, TX (US)

(73) Assignee: **PACCAR Inc**, Bellevue, WA (US)

(**) Term: **15 Years**

(21) Appl. No.: **29/530,910**

(22) Filed: **Jun. 22, 2015**

(51) LOC (10) Cl. **12-08**

(52) U.S. Cl.

USPC **D12/181**

(57) **CLAIM**

The ornamental design for a side panel roof fairing, as shown and described.

DESCRIPTION

FIG. 1 depicts a perspective view of a right side panel embodiment of the side panel of roof fairing according to our new design;

FIG. 2 depicts a front view thereof;

FIG. 3 depicts a top view thereof;

FIG. 4 depicts a left side view thereof;

FIG. 5 depicts a right side view thereof; and

FIG. 6 depicts a horizontal cross-sectional view thereof.

FIG. 7 depicts a perspective view of a left side panel embodiment of the side panel of roof fairing according to our new design;

FIG. 8 depicts a front view thereof;

FIG. 9 depicts a top view thereof;

FIG. 10 depicts a right side view thereof;

FIG. 11 depicts a left side view thereof; and,

FIG. 12 depicts a horizontal cross-sectional view thereof.

The broken lines show portions of the fender skirt which form no part of the claimed design.

1 Claim, 8 Drawing Sheets
